Primary Examiner — Amber R Stiles*Assistant Examiner* — Molly K. Orzechowski(74) Attorney, Agent, or Firm — Banner & Witcoff, Ltd.(57) CLAIM

The ornamental design for a shoe as shown and described.

DESCRIPTION

FIG. 1 is a rear perspective view of a shoe showing my new design;

FIG. 2 is a rear view thereof; and,

FIG. 3 is an opposite side rear perspective view thereof. The broken line immediately adjacent to the bottom of the shaded area defines a lower bound of the claimed design and forms no part thereof. The broken lines depicting the remainder of the shoe form no part of the claimed design.

1 Claim, 3 Drawing Sheets(56)
